Frank J. Schmid
ATTORNEY

UNITED STATES PATENT OFFICE.

PETER C. CHRISTENSEN, OF HARTFORD, CONNECTICUT.

COUNTING CARD TABLE.

Application filed June 27, 1923. Serial No. 647,095.

To all whom it may concern:

Be it known that I, PETER C. CHRISTENSEN, citizen of the United States of America, residing at 19 Baltimore Street, Hartford, 5 in the county of Hartford and State of Connecticut, have invented certain new and useful Improvements in Counting Card Tables, of which the following is a specification.

This invention relates to a counting card 10 table among the objects of the invention being the provision of simple and effective means which can be readily operated to obtain an accurate score of several players playing upon the table. The table can of 15 course be used with any card game, such as bridge whist or auction pitch.

In the drawing accompanying and forming part of the present specification there is 20 illustrated an advantageous form of embodiment of the invention which, to enable those skilled in the art to practice the same, will be set forth fully in the following description. Clearly, I am not restricted to this disclosure. I may depart therefrom in 25 several respects within the scope of the invention defined by the claim following said description.

Referring to said drawing:

Fig. 1 is a plan view of a table involving 30 the invention.

Fig. 2 is a side elevation of the table with the top broken away.

Fig. 3 is a cross section on the line 3—3 of Fig. 1.

Fig. 4 is a cross section on the line 4—4 of Fig. 1.

Fig. 5 is a detail cross section on the line 5—5 of Fig. 4.

Fig. 6 is a top plan view of a counting 40 strip.

Fig. 7 is a side elevation of the same.

Fig. 8 is a section on the line 8—8 of Fig. 6.

Like characters refer to like parts 45 throughout the several views.

The table may vary somewhat as to shape and size. That shown is denoted in a general way by 2. It comprises a top 3 of practically rectangular construction and having 50 at its corners the supporting legs 4 of which, as shown, there are four to support the table. The top is practically of rectangular formation although, as will be inferred, this is not an important matter for it can be any other 55 shape. The top has through it sight open-

ing 5 in which as shown is situated a glazed piece 6 which rests on the bottom 7 through which is a sight opening 8 which extends across the portion 7 and through which the symbols, usually numerals, upon counting strips can be read.

There may be any number of these counting strips as 9. As shown in Fig. 1, there are eight of such counting strips 9. At one side of the center of the counting strips they 65 are supported by the strip 10 while at the other side they are carried upon the strip 11, both strips being slightly slotted in their upper sides to receive the counting strips 9. The supporting strip 10, as shown, 70 is attached as by screws 13 to the under side of the table top 3 at one side of its transverse center, as clearly shown in Fig. 1.

At the opposite sides, the counting strips are carried by the supporting strip 11. 75 Under the supporting strip 11 is mounted a bar 14 which is attached to the strip 11 by the bolts 15 having at their lower ends nuts which act against the under side of the bar 14 near the ends thereof. Between the 80 bar 14 and strip 11 is arranged a row of coiled springs 16 which constantly press the bar 11 upwardly.

The counting strips 9 are in the form of bars channeled on their upper sides and 85 ordinarily bearing at their centers the symbol "0" and at opposite sides of which extend numerals running from one to nine, although anything of a like character can be printed on the strips 9. The strips 9 have 90 at their ends the downwardly extensions or fingers 17 which can be grasped to move a counting strip in either direction, that is either toward the left or the right in Fig. 1 and the strips 9 will be held frictionally in 95 the positions into which they have been moved by the hand of a user of the table.

What I claim is:

In a counting table having a top with a slot through it; a plurality of counting 100 slides supported by the top below the same, each slide having numbers running oppositely from zero upwardly and made visible through said slot by movement of the slides, resilient frictional detents supported by an 105 adjustable strip below the slides and means for simultaneously adjusting the resiliency of the detents.

In testimony whereof I affix my signature.

PETER C. CHRISTENSEN.
